UNITED STATES PATENT OFFICE.

ARNOLD A. WHEELOCK, OF WASHINGTON, DISTRICT OF COLUMBIA.

HITCHING-POST.

SPECIFICATION forming part of Letters Patent No. 366,052, dated July 5, 1887.

Application filed May 10, 1887. Serial No. 237,744. (No model.)

To all whom it may concern.

Be it known that I, ARNOLD A. WHEELOCK, a citizen of the United States, residing at Washington, in the District of Columbia, have 5 invented certain new and useful Improvements in Hitching-Posts, of which the following is a specification, reference being had thereto to the accompanying drawings.

My invention relates to improvements in 10 hitching-posts.

The object of my invention is to produce a hitching-post which will contain the hitching chain or strap so that it can be drawn out a portion of the way for use, but when not in 15 use is securely confined inside of the post, so that small boys cannot draw it out or tamper with it, as will more fully hereinafter appear.

Referring to the drawings, Figure 1 is a view in perspective of my improved hitching-post. Fig. 2 is a vertical sectional view. Fig. 20 3 is a top or plan view of the spring-actuated slide, which not only acts as a shelf for the support of the weight when the chain is in use, but also as a lock to prevent the chain from 25 being drawn out.

A indicates the main body of the post, which may be made of cast-iron or of any other suitable material, and is, by preference, cylindrical in form throughout its main portion, the 30 upper portion being square or of any other suitable shape to receive the cap B, which may be secured thereto by means of screws, bolts or in any other suitable manner. The object of making the top portion of the post 35 or the cap square is to have parallel sides, so that the valve or shelf H can be drawn out when desired, as will more fully appear.

C is the hitching chain or strap provided with the button or enlarged portion D, and 40 having the weight E secured to its lower end and a ring or snap-hook, F, at its upper end. The hitching strap or chain passes over the cross-bar G, secured in the cap or cover B and through an opening in the shelf H, while 45 the weight E, secured to the lower end of the chain, rests on the ledge I in the main body of the post.

H is a metal plate or shelf adapted to work through a slot, a, formed in the cap B or in 50 the upper portion of the post A, said shelf being turned down at its rear end, so as to form a flange, K. The flange K is provided

with holes at or near each side to receive the rods L, said rods being provided with springs M, one end of which presses against the flange 55 K, while the other end of the springs rests against the inside of the cap or post, thus serving to keep the shelf in position. The front end of the shelf H is provided with a slot, b, which serves as a hand-hold, while the rear end of said shelf is cut out to form the opening c, through which the weight E is drawn when the shelf is pulled out.

d is a contracted opening forming a portion of the opening c, for the reception of the 65 chain C. The opening d is smaller than the button D, so that when the chain is not in use the button will be below the shelf, which prevents its withdrawal until the shelf is drawn back, so that the button can pass through the 70 opening c. In operating this device, the shelf is drawn forward, so that the chain can be pulled up and the weight E raised above the shelf or slide H. The shelf is now released, and is returned to its normal position by the 75 springs M, when the weight E is allowed to rest on said slide or shelf, the upper end of the chain being drawn through the hole N in the cap B and secured to the bridle or bit of the animal. After the chain is released and 80 the animal unhitched, the slide or shelf is drawn out again and the weight E pushed off by coming in contact with the bar G, or with the side of the cap B, so that it will drop down into the post A and rest on the ledge I. The 85 shelf H is now released, and is forced back into its normal position, as has been already explained.

Having thus described my invention, what I claim, and desire to secure by Letters Patent, 90 is—

1. A hitching-post having an interior cavity for the reception of the hitching chain or strap and a spring-actuated shelf in its upper portion, said shelf being provided with an aperture through which a weight or block on the lower end of the chain is permitted to pass, 95 as set forth.

2. A hitching-post having an interior cavity and a cap for covering the same, said cap being 100 provided with an opening through which the upper end of the hitching-chain is passed, a weight secured to the lower end of the chain, and a spring-actuated sliding shelf having an

opening which allows the weight to be raised above the shelf and be held in such raised position by the shelf when the same is returned to its normal position, as set forth.

5. A hitching-post of the character described, provided with a spring-actuated shelf, said shelf being provided with apertures *c* and *d*, in combination with a hitching chain or strap provided with a button or enlarged por-

tion, *D*, whereby the chain is held within the post and cannot be withdrawn until the shelf is drawn back, as set forth.

In testimony whereof I affix my signature in presence of two witnesses.

ARNOLD A. WHEELOCK.
